(57) **CLAIM**

The ornamental design for a tire, as shown and described.

DESCRIPTION

FIG. 1 is the front elevational view of a tire, for which the other sides, rear elevational view is the same;
FIG. 2 is a top elevational view thereof, for which the other sides, bottom elevational view is the same;
FIG. 3 is a left side view thereof, for which the other sides, right side view is the same;
FIG. 4 is an enlarged fragmentary top elevational view thereof; and,
FIG. 5 is a perspective view of a tire showing the new design, it being understood that the pattern repeats uniformly throughout the circumference of the tread.
